MANDREL AND LOCK FOR A HAIR CURLER

William Hamilton Cooper, Buffalo, N. Y.

Application October 24, 1932, Serial No. 639,346

36 Claims. (Cl. 132—33)

This invention relates to hair curlers of the type used in connection with permanent wave machines and more particularly to a mandrel about which a lock of hair is to be coiled having associated therewith a lock for engaging the hair which is coiled about the mandrel.

One object of the invention is to provide a mandrel having associated therewith a lock of such construction that hair may be firmly gripped and held when it is being coiled about the mandrel.

Another object of the invention is to so construct the lock that by holding a portion of the lock with the fingers of one hand and turning the mandrel with the other hand, a movable element of the lock may be very easily moved into or out of an operative position and when moved to an operative position, not be liable to accidentally slip and return to a position in which the hair will be released.

Another object of the invention is to provide a device of this character which is very simple in construction and easy to operate.

The invention is illustrated in the accompanying drawings, wherein:

Figure 1 is a view showing one embodiment of the invention in side elevation;

Figure 2 is a sectional view taken transversely through the mandrel along the line 2—2 of Figure 1;

Figure 3 is a view similar to Figure 2, showing the latch moved to an operative position;

Figure 4 is a bottom plan view of the mandrel and lock;

Figure 5 is a sectional view through the lock taken along the line 5—5 of Figure 6;

Figure 6 is a sectional view through the lock and a portion of the mandrel, taken along the line 6—6 of Figure 2;

Figure 7 is a view showing a portion of the mandrel and the elements forming the lock in perspective;

Figure 8 is a side elevation of a modified form of the improved mandrel and lock;

Figure 9 is a sectional view taken through the mandrel along the line 9—9 of Figure 8, looking toward the lock;

Figure 10 is a view similar to Figure 9, showing the latch element of the lock moved to its operative position;

Figure 11 is a view looking at the under face of the lock;

Figure 12 is a view similar to Figure 9, with the upper plate of the housing or body portion of the lock removed, and showing the latching element in its retracted or inoperative position;

Figure 13 is a view similar to Figure 12 showing the latching element moved to its operative position;

Figure 14 is a sectional view taken transversely through the lock along the line 14—14 of Figure 12;

Figure 15 is a perspective view of a portion of the mandrel and the elements forming the lock of this embodiment of the invention;

Figure 16 is a side elevation of another modified form of the invention;

Figure 17 is a sectional view taken through the mandrel along the line 17—17 of Figure 16, with a keeper forming part of the latch swung to an open position;

Figure 18 is a view similar to Figure 17 showing the keeper moved to its retracted or operative position;

Figure 19 is a view looking at the bottom of the lock;

Figure 20 is a view taken through the lock along the line 20—20 of Figure 21;

Figure 21 is a sectional view taken along the line 21—21 of Figure 20;

Figure 22 is a perspective view of the lower portion of the mandrel and the elements forming the lock;

Figure 23 is a side elevation of still another modified form of the improved mandrel and lock;

Figure 24 is a view taken through the mandrel of Figure 23, looking toward the lock, and showing a keeper forming part of the lock moved to an opened position;

Figure 25 is a view similar to Figure 24 showing the keeper in a closed position;

Figure 26 is a bottom plan view of the mandrel and lock shown in Figure 23;

Figure 27 is a sectional view taken transversely through the lock and a portion of the mandrel along the line 27—27 of Figure 25; and

Figure 28 is a perspective view of the elements forming the lock, together with a portion of the mandrel shown in section;

Figure 29 is a side elevation of another modified form of curler;

Figure 30 is a sectional view on an enlarged scale taken along the line 30—30 of Figure 29, showing a hair gripper in a closed position;

Figure 31 is a view similar to Figure 30, showing the hair gripper moved towards an opened position;

Figure 32 is a similar view showing the hair gripper in its fully opened position;

Figure 33 is a sectional view taken along the line 33—33 of Figure 30;

Figure 34 is a view similar to Figure 33 showing the mandrel moved to an adjusted position;

Figure 35 is a perspective view of the elements forming the curler, taken apart.

5 In describing the invention, I shall refer to the drawings in which similar reference characters designate corresponding parts throughout the several views.

The curler illustrated in Figures 1 through 7 10 has a mandrel 1 formed of metal. This mandrel may be of any length and diameter desired and for the major portion of its length is circular in cross section and of the same diameter. Its upper end is reduced to form a finger hold 3 which is 15 also circular in cross section and its lower end is reduced to form a neck 4 which is rectangular in cross section and formed with a threaded socket 5 to receive a screw 6 as shown in Figure 6.

The hair engaging lock which is associated 20 with the spindle is also formed of metal and consists of a disc 7 which turns relative to the mandrel and upper and lower discs 8 and 9 firmly carried by the neck 4 and formed with rectangular openings 10 and 11 to receive the neck.

25 Referring to Figure 6, it will be seen that when the discs 8 and 9 are applied to the neck and the screw 6 screwed into the socket 5 with its head bearing against the under face of the disc 9, the two discs will be prevented from moving off of 30 the neck and since the disc 8 is formed with a hub 12 against which the disc 9 bears, the two discs will be retained in spaced relation to each other and the disc 7 which is disposed between the discs 8 and 9 and formed with an enlarged 35 opening 13 to receive the hub of the disc 8 will be permitted to turn freely between the discs 8 and 9 relative to these discs when the disc 7 is grasped by its flange 14 and motion imparted to rotate this disk relative to the mandrel and discs 8 and 40 9. A flange 15 is formed about margins of the disc 8 to bear against the flange 14 as shown in Figure 6 and referring to this figure, it will be seen that the flange 14 not only extends upwardly above the disc 7 but also projects downwardly 45 to encircle the disc 9. Therefore, the disc 7 will be prevented from tilting transversely upon the hub 12 and will be permitted to rotate freely relative to the discs 8 and 9. The opening 13 formed in the disc 7 is extended to form a throat 16 opening through the marginal flange 14 of this disc and this throat is intended to register with slots 17 and 18 formed in the discs 8 and 9. It will be noted that the slots 17 and 18 are so cut that their inner ends are extended at one side as shown at 50 19 and 20, thereby causing these discs to be formed with fingers 21 and 22 which are intended to extend across a lock of hair and force the hair into the inner end portion of the side extension 16' of the slot 16. This side extension is gradually reduced in width towards its inner end and therefore the hair will be firmly wedged into this portion of the slot 16 when the curler is in use. Referring to Figures 4 and 7, it will be seen that from the outer end portion of the finger 22 projects a lug 23 which bears against the lower portion of the flange 14 as the disc 7 is turned and by contacting with a tooth or abutment 24 struck inwardly from the flange 14, will serve to limit rotation of the disc in either direction. Therefore, proper registration of the slots 16, 17 and 70 18 will be assured and also rotation of the discs relative to each other in a closing direction will be limited.

When this device is in use, the disc 7 is grasped 75 by holding its flange 14 between a thumb and one

or two fingers of one hand and by grasping the knob 3 of the mandrel between fingers of the other hand, the mandrel and disc 7 may be rotated relative to each other in a direction which will dispose the slots of the three discs in alignment as shown in Figure 2. A lock of hair can then be drawn forwardly through the aligned slots and turning motion then imparted to the mandrel to rotate the discs 8 and 9 and cause the slots to be closed and the lock of hair firmly held. This lock of hair is then coiled about the mandrel by use of a winder or in any other desired manner after which it will be covered with a wrapper dipped in chemical and thrust into a heating element of a permanent waving machine. It will, of course, be understood that the hair can be first engaged through the aligned slots and coiled about the mandrel after the slots have been closed or the hair coiled about the mandrel and then engaged through the slots and the discs 10 15 20 25 30 35 40 45 50 55 60 65 70 75 80 85 90 95 100 turned to close the slots. This is optional with the operator.

The form of curler illustrated in Figures 3 through 15 is in many respects similar to that previously described and has a mandrel 25 formed with a turning head 26 at its outer end and a reduced rectangular neck 27 at its inner end. The lock carried by the inner end portion of the mandrel is of a different construction from that shown in Figures 1 through 7 and consists of a housing 23 having upper and lower walls 29 and 30, the lower wall carrying a marginal wall or flange 31 which is reduced in thickness to form a seat 32 against which the wall 29 bears and extended inwardly as shown in Figure 14 to overlap the disc or wall 30 35 40 45 50 55 60 65 70 75 80 85 90 95 100 29 and retain it in engagement with the marginal wall of the housing. Between the walls 29 and 30 of the housing is located a disc 33 formed with a rectangular opening 34 to receive the neck of the rod or mandrel and this disc is firmly fixed upon the neck to prevent movement of the rod outwardly through the opening 35 formed in the disc or wall 29. Therefore, by holding the housing and imparting rotary motion to the mandrel, the disc 33 may be rotated within the 45 housing and the finger 36 moved across from the position shown in Figure 12 to that disclosed in Figure 13. When the disc 33 is cut to form the finger 36, there is also provided a slot 39 adapted to register with the slots 37 and 38 in order that hair may be engaged through the lock prior to movement of the disc 33 to the position shown in Figure 13 and in order to limit rotation of the disc within the housing, there has been provided a pin 40 which projects inwardly to engage abutments 41 and 42 corresponding to the abutments 23. Since the slot 39 has a portion 39' extending about the disc and reduced in width towards its inner end and the slots 37 and 38 have side extensions 37' and 38', hair will be wedged in 60 65 70 75 80 85 90 95 100 these portions of the slots and firmly gripped. The operation of this form of curler need not be described as it is similar to that of the device illustrated in Figures 1 through 7.

The curler illustrated in Figures 16 through 21 also has a mandrel or rod 43 carrying a lock 44 at one end, but the lock is quite different in its construction from those previously described. In this embodiment of the invention, the lock consists of a housing 45 having an upper wall 46 which fits within the marginal wall 47 rising from the bottom of the housing. A flange 48 projects upwardly from margins of the upper wall 46 and about this flange is formed a bead 49 which rests against the wall 47. The inner end 75

portion of the mandrel 43 extends through an opening 56 formed centrally of the wall 45 into the housing and the end of the mandrel terminates in a squared neck 51 which engages through a rectangular opening 52 formed in the hub 53 of a latch 54. By referring to Figures 20 and 22, it will be seen that the latch is formed with a longitudinally curved bill 55 extending circumferentially of the housing in radial spaced relation to the rod.

An opening 56 is formed centrally of the wall 45 of the housing and through this opening is passed a screw 57 which is screwed into a socket 58 formed axially of the rod and has its head 59 overlying portions of the hub 53 about the neck 51 to firmly hold the latch upon the neck and prevent the rod from slipping out of the lock.

A lock of hair is to be passed through the housing similar to the manner in which hair is drawn through the lock previously described and in order to do so, the bottom 45 of the housing and its upper wall or cover 46 have been formed with aligned slots 58 and 59. At one side of these slots, the marginal wall 47 is cut away to receive the hinge ear 60 of a keeper 61 through which extends a screw or pivot pin 62 carried by hinge ears 63 and 64 formed upon the bottom and upper walls, and, therefore, the keeper will be pivotally mounted for swinging movement into and out of a closed position as shown in Figures 17 and 18. The marginal wall of the housing is also cut away at the opposite side of the slot to permit the bill 65 of the keeper to swing inwardly and between its hinge ear 60 and bill 65, the keeper is formed with side flanges 66 between which engage the bill of the latch when the latch is moved into locking engagement with the keeper.

When this form of curler is in use, the lock of hair is passed through the slots of the housing and its cover or upper wall and coiled about the mandrel as previously described. In order to secure the hair in position through the lock, the keeper is swung inwardly towards a closed position after the hair has been engaged through the slots 58 and 59. The housing and mandrel can then be turned relative to each other in a direction to move the bill of the latch across the aligned openings and as this movement takes place, the bill 55 will overlap the bill 65 of the keeper and exert a cam action which will force the keeper inwardly until the hair is very firmly gripped between the keeper and inner ends of the slots of the housing.

Since the free end portion of the bill 55 engages between the side flanges 66 of the keeper, transverse movement of the latch and keeper relative to each other will be prevented and the keeper will be forced inwardly towards a closed position without danger of side strain which might bend or break the pivot pin. When the rod and housing are turned in an opposite direction relative to each other, the keeper will be released and may be swung outwardly to an open or inoperative position, thereby releasing the hair and permitting it to be drawn outwardly from the housing.

In the curler illustrated in Figures 23 through 28 a rod 66 is employed which tapers from its lower end for a short distance and by referring to Figure 27, it will be seen that this lower end is enlarged as shown at 67 to form a head bored to provide a socket 68 communicating with a passage 69 extending axially through the rod from the socket to the upper end of the rod. The lower end portion 70 of the socket is addi-

tionally enlarged in diameter, thereby forming a seat to rotatably receive a neck 71 projecting upwardly from the center of the top or upper wall 72 of the housing 73 forming the body portion of a lock 74 corresponding to the lock 44.

The cover or upper wall 72 rests upon the marginal wall 75 of the housing where it is held in place by a screw 76 engaged through hinge ears 77 and 78 and serving as a pivot pin for a keeper 79 corresponding to the keeper 61. A flaring flange or marginal wall 80 projects upwardly about margins of the cover or upper wall 72 with its ends terminating at opposite sides of a slot 81 formed in this cover and from one of the side arms or wings 82 of the keeper 79 extends a lip 83 forming a continuation of the wall 80 when the keeper is swung inwardly to the closed position shown in Figures 25 and 27.

By referring to Figure 27, it will be seen that when the keeper is in a closed position, it moves into the slot 81 of the cover 72 and also into a corresponding slot 84 formed in the bottom of the housing 73. A key or rod 85 carrying a latch 86 at its lower end which is firmly fixed to the same extends through the hollow stem or mandrel 25 and by rotating the stem the bill 87 of the latch may be moved into and out of position to overlie the keeper and secure the same in a closed position with a lock of hair gripped between the keeper and inner end of the slot formed in the upper wall or cover and bottom of the housing. The rod or stem 85 is of such length that it projects beyond the upper end of the rod or stem and upon this protruding upper end of the rod which is squared as indicated by dotted lines 35 in Figure 23, is applied a finger engaging element 88 which is removable in order that the rod may be slid longitudinally through the mandrel when it is necessary to remove the mandrel.

Wings 89 which are preferably four in number 40 project radially from the upper end portion of the rod to permit this rod to be readily rotated when the lock 74 is held between a thumb and finger of one hand and the wings gripped between a thumb and finger of the other hand, 45 and in order to control rotation of the rod, there has been provided a coiled spring 90 firmly seated in the collar 71 which serves as a bearing for the lower end of the rod and this spring extends into the socket 68 with its free end in 50 contact with walls of the socket. By this arrangement, the rod or stem may be readily rotated in one direction about the stem and collar 71 but if it is attempted to turn the rod in an opposite direction the sharp free end of the 55 spring will bite into walls of the socket and prevent rotation in this direction. Therefore, the rod can only be turned in one direction and a lock of hair engaged through the lock 74 will be coiled in a proper direction about the rod. 60 A tongue 91 formed of thin sheet metal extends longitudinally of the rod and this tongue which is curved transversely in order to fit closely about the rod as shown in Figures 24 and 25 is pivotally mounted at one end to the rod a short distance from the inner ends of the wings 89 as 65 shown at 92. Therefore, when a lock of hair is to be coiled about the rod, its free end portion may be first engaged between the rod and the tongue 91 and firmly gripped by the tongue during 70 a coiling operation. Therefore, the hair will be firmly held and prevented from slipping during or after it has been coiled.

When this form of curler is in use, a lock of hair is passed through the slots 84 and 81 of 75

the cover 12 and housing 13 after the keeper 19 has been swung towards the closed position shown in Figure 5, the head or finger engaging element 28 of the stem will be grasped and rotary motion 5 imparted to the stem to swing the bill 37 of the latch toward the keeper and cause the bill to move to overlapping engagement with the keeper and force the keeper tightly into place within the housing of the lock. The free end portion 10 of the lock of hair is then engaged between the rod and the tongue 91 and by grasping the wing 89 the rod can be easily rotated in a counter-clockwise direction and cause the lock of hair to be coiled tightly about the rod. Either a 15 croquignole coil or any other type desired may be formed by properly guiding the lock of hair during a curling operation.

The curler illustrated in Figures 29 through 35, has a mandrel 91^a formed of metal or any other 20 suitable material and at the lower end of this mandrel is provided a lock 92^a for connecting the mandrel with a lock of hair to be curled. The lock has upper and lower plates 93 and 94, the plate 93 being formed with a depending hub 95 25 terminating in a squared neck 96 received in a square opening 97 formed centrally of the plates or discs 94. This hub 95 retains the plates spaced from each other and since the plate or disc 94 is carried by a squared neck, the two plates will 30 turn as a unit. A screw 98 serves to hold the lower plate in place about the neck and by being screwed into a threaded socket 99 formed in a stem 100, serves to connect the stem with the upper plate. This stem fits into a seat or socket 35 91^b formed centrally of the upper plate and about this socket is formed an annular groove 102, serving as a seat for the inner end of the mandrel and when this mandrel is seated in the annular groove, frictional engagement will take 40 place and cause the two plates to turn with the mandrel. By exerting pull upon the mandrel, it may be readily separated from the lock and drawn away from the same to release a coil of hair after a curling operation has been completed. 45

Referring to Figures 33 and 34, it will be seen that the stem 100 is received in a pocket 103 formed longitudinally of the mandrel from its inner end and this stem slides through a bushing 50 104 which fits tightly within the pocket of the mandrel and serves to guide sliding movement of the mandrel toward and away from the lock. The bushing also serves to engage a head 105 carried by the stem and prevents sliding movement 55 of the mandrel away from the lock beyond the position shown in 34. By this arrangement, a lock of hair may be coiled tightly about the mandrel with the mandrel in the position shown in Figure 33 and after a curling operation is finished, the mandrel may be drawn through the coil of hair to the position shown in Figure 34, thereby 60 releasing frictional grip of the hair and permitting it to expand sufficiently to break its grip and allow the mandrel to be slid out of the curl. 65 If so desired, the mandrel may be directly secured to the upper plate as previously shown and described instead of being mounted for movement towards and away from the lug.

The plates 93 and 94 cooperate to form a housing 70 between which a keeper 106 is pivotally mounted for movement from an opened position shown in Figure 32 towards a closed position shown in Figure 30, in which the keeper extends circumferentially of the housing across hair receiving recesses 107 and 108 cut radially of the

plates or discs and having side extension 109 and 110 into which the hair is to be forced and firmly gripped when the device is in use. When a lock of hair is engaged through the opposed hair receiving recesses of the plates or walls of the housing, the keeper is to be moved inwardly and forced into tight gripping engagement with the hair. In order to do so, there has been provided a band or collar 111 which fits snugly about the housing in contacting engagement with marginal edges of the upper and lower walls and referring to Figures 33 and 34, it will be seen that this collar or band is formed with an inwardly projecting, circumferentially extending lip 112 which projects into the space between these walls and prevents movement of the collar out of its proper engagement with the housing. An upstanding marginal flange 113 carried by the upper wall or plate also bears against the collar and assists in retaining the collar in proper engagement with the two walls and guiding rotation of the collar. Ends of the collar or band terminate in spaced relation to each other a distance slightly greater than the width of the hair receiving recess of the housing in order that easy access 20 may be had to the hair receiving recess when fitting a lock of hair into the same. 25

Referring to Figures 30, 31 and 32, it will be seen that as one end of the band, the lip 112 and face of the band are cut straight across 30 diagonally to form an undercut cam surface 114, whereas at the other end of the collar the lip is gradually reduced in width to form a cam surface 115. By this arrangement, a lock of hair may be engaged through the recesses of the plates 93 and 94 and by holding the band or collar with the thumb and fingers of one hand and turning the mandrel with the other hand in the direction indicated by the lower arrow in Figure 31, the keeper or tongue 106 will be guided inwardly by the cam surface 115 and moved inwardly across the hair receiving recesses to a position in which the lock of hair will be forced into the end portions 109 and 110 of the recesses and firmly gripped. 40

When the mandrel is rotated in the opposite direction indicated by the upper arrow in Figure 31, the free end of the keeper which is bevelled as shown at 116 will make contact with the bevelled end face 114 and be guided outwardly 50 towards the opened position as shown in Figure 31 and finally moved to the fully opened position shown in Figure 32. By this arrangement, the tongue or keeper moves automatically into and out of a position across the hair receiving recesses and the device can be very easily engaged with or disconnected from a lock of hair. 55

Insofar as the croquignole winding device, as illustrated particularly in Figures 23 to 28, inclusive, is concerned, the important feature of the device is the linking together of a lock directly on the shaft, rod or mandrel upon which the croquignole winding of the hair is accomplished. Whereas, heretofore it has been necessary to utilize a separate locking element into which the hair curling rod is inserted in order to lock the hair on the rod and the rod in position with respect thereto, I have provided a device in which there is a combination lock and hair curling lock for croquignole winding. Such a combination 70 device saves time, labor and expense in operation and will eliminate the possibility of burning the scalp, which quite frequently occurs through the use of the well known separable locking elements used on hair curling mandrels or rods. 75

From the foregoing description of the construction of my improved device, the method of applying the same to use will be readily understood. It will be seen that I have provided a simple, inexpensive and efficient means for carrying out the objects of the invention and while I have particularly described the elements best adapted to perform the functions set forth, it is obvious that various changes in form, proportion and in the minor details of construction may be resorted to, without departing from the spirit or sacrificing any of the principles of the invention.

Having thus described the invention, what is claimed is:

1. A device for attaching a curling mandrel to a lock of hair comprising rigid plates spaced from each other and formed with opposed hair receiving recesses leading from their margins, and a flat rigid plate between the first plates formed with a hair receiving recess and rotatable concentric to the first plates into and out of position to cause hair to be confined in the recesses of the plates and firmly gripped by the plates.

2. A device for attaching a curling mandrel to a lock of hair comprising plates spaced from each other and formed with opposed hair receiving recesses leading from their peripheries radially of the plates and having transversely extending side extensions at their inner ends, and another plate rotatably mounted between the first plates and formed with a hair receiving recess leading from its periphery, the recesses being moved into position to close their outer ends and confine hair in the recesses when the plates are rotated relative to each other in one direction.

3. A device for attaching a curling mandrel to a lock of hair comprising plates spaced from each other and formed with opposed hair receiving recesses leading from their peripheries radially of the plates and having transversely extending side extensions, and another plate rotatably mounted between the first plates concentric thereto and formed with a hair receiving recess leading from its periphery, said plates bracing each other against transverse shifting and when turned in one direction closing outer ends of the recesses.

4. A device for attaching a curling mandrel to a lock of hair comprising a pair of plates spaced from each other and a plate rotatably mounted between the first plates, said plates bracing each other to prevent radial shifting thereof and having hair receiving recesses leading from their peripheries and moved into position to close their outer ends when the plates are rotated in one direction.

5. A device for attaching a curling mandrel to a lock of hair comprising a pair of plates spaced from each other and a plate rotatably mounted between the first plates, one plate having a marginal flange engaging the other plates to prevent transverse shifting of the plates, and said plates being formed with hair receiving recesses leading from their margins and moved into position to close their outer ends when the plates are turned in one direction relative to each other.

6. A device of the character described comprising a mandrel, and means for attaching the mandrel to a lock of hair to be coiled about the mandrel consisting of a set of plates spaced from each other and another plate disposed between the first plates and rotatable relative to the same, said plates being formed with hair receiving slots having transversely extending portions to cause

hair to be firmly wedged in the slots when the disks are turned relative to each other in one direction.

7. A device of the character described comprising a mandrel, and means for attaching the mandrel to a lock of hair to be coiled about the mandrel consisting of a set of plates spaced from each other and another plate disposed between the first plates and rotatable relative to the same, said plates being formed with hair receiving slots extending radially of the disks from their margins and having side extensions in which hair is wedged and firmly gripped when the disks are turned relative to each other in one direction.

8. A device of the character described comprising a mandrel, and means for attaching the mandrel to a lock of hair to be coiled about the mandrel consisting of a set of plates spaced from each other and another plate disposed between the first plates and rotatable relative to the same, said plates being formed with hair receiving recesses opening through peripheries of the plates and moved into and out of position to close their outer ends and confine hair within the recesses by rotating the plates.

9. A device of the character described comprising a mandrel and means for attaching the mandrel to a lock of hair consisting of a pair of plates fixed to one end of the mandrel in spaced relation to each other and having opposed hair receiving recesses leading from their margins, and a plate rotatably mounted between the spaced plates and formed with a hair receiving recess leading from its periphery and moved into position to confine hair within the recesses when the plate is turned in one direction.

10. A device of the character described comprising a mandrel and means for attaching the mandrel to a lock of hair consisting of a pair of plates fixed to one end of the mandrel and one plate having a hub engaging the other plate to retain the plates spaced from each other, and another plate between said plates rotatable about the hub, said plates being formed with hair receiving slots in which hair is confined and gripped when the rotatable plate is turned in one direction.

11. A device of the character described comprising a mandrel and means for attaching the mandrel to a lock of hair consisting of upper and lower discs fixed upon the lower end of said mandrel and the upper disc having a hub holding the discs spaced from each other and an upstanding marginal flange, and an intermediate disc rotatable about the hub of the upper disc and formed with a marginal flange engaging the flange of the upper disc and marginal edge of the lower disc, said discs having hair receiving slots leading from their peripheries in which hair is confined and gripped when the intermediate disc is turned in one direction.

12. A device of the character described comprising a mandrel and means for attaching the mandrel to a lock of hair consisting of upper and lower discs fixed upon the lower end of said mandrel and the upper disc having a hub holding the discs spaced from each other and an upstanding marginal flange, and an intermediate disc rotatable about the hub of the upper disc and formed with a marginal flange engaging the flange of the upper disc and marginal edge of the lower disc, said discs having hair receiving slots leading from their peripheries in which hair is confined and formed with side extensions to cause

the hair to be firmly gripped when the intermediate disc is turned in one direction.

13. A device of the character described comprising a mandrel and means for attaching the 5 mandrel to a lock of hair consisting of upper and lower discs rotatably engaged about the lower end portion of the mandrel and an intermediate disc fixed to the mandrel and rotatable between the upper and lower discs, the upper and 10 lower discs being united about their margins and said discs being formed with hair receiving slots leading from their margins and moved into position to confine and grip hair when the intermediate disc is rotated in one direction.

14. A device of the character described comprising a mandrel and means for attaching the mandrel to a lock of hair consisting of upper and lower discs rotatably engaged about the lower end portion of the mandrel and an intermediate 20 disc fixed to the mandrel and rotatable between the upper and lower discs, the lower disc having an upstanding marginal wall engaging the upper disc to retain the upper and lower disc spaced from each other and confine the intermediate 25 disc between the same, said discs being formed with hair receiving slots having side extensions and being moved into position to confine and grip hair when the mandrel is rotated to turn the intermediate disc, and an abutment projecting from 30 the marginal wall to engage the intermediate disc and limit rotation thereof.

15. A device of the character described comprising a mandrel and means for attaching the mandrel to a lock of hair consisting of a housing 35 having upper and lower walls and a marginal wall, said mandrel having its lower end extending into the housing through the upper wall and the housing being rotatable about the mandrel, said housing being formed with a hair receiving recess leading from its periphery, a keeper movable into and out of said recess, and a latch for said keeper in the housing and movable into and out of position to secure the keeper by rotation of the mandrel.

16. A device of the character described, comprising a mandrel and means for attaching the mandrel to a lock of hair consisting of a housing having upper and lower walls and a marginal wall, said mandrel having its lower end extending 40 into the housing through the upper wall and the housing being rotatable about the mandrel, said housing being formed with a hair receiving recess leading from its periphery, a keeper pivoted to the housing for movement into and out of the recess, and a latch fixed to the mandrel within 45 the housing and movable into engagement with the keeper when the mandrel is rotated in one direction.

17. A device of the character described comprising a mandrel, and means for attaching the 60 mandrel to a lock of hair consisting of a housing rotatable about the lower end of said mandrel and formed with a hair receiving recess leading from its periphery, a keeper movable into and 65 out of said recess and a latch for said keeper carried by said mandrel within the housing and retaining the housing in engagement with the mandrel.

18. A device of the character described comprising a mandrel, and means for attaching the 70 mandrel to a lock of hair consisting of a housing rotatable about the lower end of said mandrel, a hair gripper carried by said housing and movable into and out of a gripping position, and a 75 latch for holding the gripper in a gripping po-

sition carried by the mandrel within the housing and movable into and out of position to engage the gripper by rotation of the mandrel.

19. A device of the character described comprising a mandrel, and means for attaching the 5 mandrel to a lock of hair consisting of a housing rotatable about the lower end of said mandrel, a hair gripper carried by said housing and movable into and out of a gripping position, and a latch for holding the gripper in a gripping position carried by the mandrel within the housing and serving to retain the housing in engagement with the mandrel.

20. A device of the character described comprising a mandrel, and means for attaching the 15 mandrel to a lock of hair consisting of a housing rotatable about the lower end of said mandrel and formed with a hair receiving recess leading from its periphery, a keeper pivoted to said housing for movement into and out of a hair gripping position within the recess and formed with outstanding flanges, and a latch fixed to the 20 mandrel within the housing and having a curved bill extending circumferentially of the housing to engage the keeper between its flanges and 25 secure the keeper in a gripping position when the mandrel is rotated in one direction.

21. In a device of the character described, a mandrel formed with an axially extending bore, a rod rotatably received in the bore, a housing 30 having the lower end of the mandrel rotatably engaged therewith, a hair engaging keeper carried by said housing and movable into and out of a gripping position, and a latch for said keeper movably mounted in the housing and connected with the rod for movement into and out of engagement with the keeper when the rod is rotated.

22. In a device of the character described, a mandrel formed with an axially extending bore, 40 a rod rotatably received in the bore, a housing formed with a hair receiving recess and rotatably engaged with the lower end of said mandrel to permit rotation of the mandrel relative to the housing, a keeper pivoted to said 45 housing for movement into and out of the recess, a latch for said keeper carried by said rod and means for controlling rotation of the mandrel.

23. In a device of the character described, a locking device formed with a hair receiving recess, a keeper movable into and out of a hair gripping position within the recess, a latch movable into engagement with said keeper, and a mandrel having its lower end rotatably engaged 50 with the locking device.

24. In a device of the character described, a locking device formed with a hair receiving recess, a keeper movable into and out of a hair gripping position within the recess, a latch movable into engagement with said keeper, a mandrel having one end rotatably engaged with the locking device and an actuating rod for said latch extending longitudinally through the 60 mandrel.

25. In a device of the character described, a locking device formed with a hair receiving recess, a keeper movable into and out of a hair gripping position within the recess, a latch movable into engagement with said keeper, a mandrel having one end rotatably engaged with the 65 locking device and means to prevent rotation of the mandrel in one direction.

26. In a device of the character described, a housing formed with a hair receiving recess leading from its periphery, a hair gripping keeper 70

5 pivoted to the housing for movement into and out of the recess, a hub extending from the center of said housing, a mandrel formed with an axially extending bore having one end enlarged to form a socket rotatably receiving the hub to mount the mandrel for rotation relative to the housing, a latch for said keeper mounted within said housing, an actuating rod for said latch extending through the bore of said mandrel and 10 having turning means at its outer end and a coiled spring carried by said hub and received in said socket with its free end bearing against walls thereof to prevent rotation of the mandrel in one direction by biting into the walls of the 15 socket.

27. A hair curler comprising a mandrel and hair gripping means at one end of said mandrel, said mandrel having connection with said hair gripping means and also having limited axial 20 movement with respect thereto.

28. A hair curler comprising a mandrel, a hair gripper and means connecting said mandrel and gripper affording rotatable and limited sliding axial movement of the former with respect to the 25 latter.

29. A hair curler comprising a mandrel, a hair gripper, and a stem extending from the center of the gripper and slidably and rotatably received in the mandrel to permit rotation of the mandrel 30 and also permit sliding movement of the mandrel away from the gripper.

30. A hair curler comprising a mandrel formed with an axially extending pocket leading from one end, a hair gripper, a stem extending from 35 the center of said gripper and slidably and rotatably received in the pocket of said mandrel to rotatably and slidably mount the mandrel, a head being provided upon said stem, and a bushing in said pocket about the stem to engage the 40 head and limit movement of the mandrel away from the gripper.

31. A hair curler comprising a mandrel formed with an axially extending pocket leading from one end, a hair gripper, a stem extending from 45 the center of said gripper and slidably and rotatably received in the pocket of said mandrel to rotatably and slidably mount the mandrel, and a bushing in said pocket about the stem engageable by the free use of the stem to limit 50 movement of the mandrel away from the hair gripper, the bushing being spaced from the outer end of the pocket and a circular groove being formed in the gripper about the stem to receive the portion of the mandrel projecting from the 55 bushing and frictionally hold the mandrel in engagement with the gripper.

32. A hair curler comprising a mandrel and means to connect the mandrel with a lock of hair to be curled consisting of a member rotatable with the mandrel and formed with a hair receiving recess, and a hair gripper moved automatically into and out of position across the recess by rotation of said member. 5

33. A hair curler comprising a mandrel and means to connect the mandrel with a lock of hair to be curled consisting of a member rotatable 10 with the mandrel and formed with a hair receiving recess, a hair gripper pivoted to said member for movement into and out of position across said recess, and a cam element extending about said member to engage said gripper and impart 15 movement to the same during rotation of the member.

34. A hair curler comprising a mandrel and means to connect the mandrel with a lock of hair to be curled consisting of a member rotatable 20 with the mandrel and formed with a hair receiving recess, a hair gripper pivoted to said member for movement into and out of position across said recess, and a band extending about said member with its ends spaced a distance approximately corresponding to the width of the outer end of said recess, said band being formed with cam surfaces to engage said gripper and move the same into and out of position across the recess when the member is rotated. 25

35. A hair curler comprising a mandrel and means for connecting the mandrel with a lock of hair to be curled consisting of a housing having upper and lower walls spaced from each other and formed with opposed hair receiving 30 recesses leading from their margins, a gripping tongue pivoted at one end between said walls at one side of the recesses, and a band rotatable about said walls with its ends spaced from each other, said band having a circumferentially extending flange fitting between the walls and having cam surfaces to engage the gripping tongue and move the same into and out of position across the recesses of the walls. 40

36. A clip for a hair waving form comprising a pair of spacedly disposed disc members having registering arcuate slots therein open at one end, a third disc mounted between said pair and rotatable relative thereto, said third disc having an arcuate slot opening at one end and having 45 a peripheral rim formed therewith, said rim overlying the peripheries of the two adjacent discs. 50

WILLIAM HAMILTON COOPER.
